UNITED STATES PATENT OFFICE.

CHARLES A. HORNBURG, OF WACO, TEXAS.

AUTO RIM ADJUSTER.

Application filed December 28, 1927. Serial No. 243,015.

It is the object of this invention to provide a simple means whereby the ends of a demountable automobile tire rim may be brought into alignment to effect a closing of the rim.

It is within the province of the disclosure to improve generally and to enhance the utility of devices of that type to which the invention appertains.

10 With the above and other objects in view which will appear as the description proceeds, the invention resides in the combination and arrangement of parts and in the details of construction hereinafter described and 15 claimed, it being understood that changes in the precise embodiment of the invention herein disclosed, may be made within the scope of what is claimed, without departing from the spirit of the invention.

20 In the drawings:—

Figure 1 shows in plan, a tool constructed in accordance with the invention;

Figure 2 is a plan showing the opposite side of the tool from that disclosed in Figure 1;

25 Figure 3 is an elevation wherein the tool is viewed edgewise;

Figure 4 is a section on the line 4—4 of Figure 1;

30 Figures 5, 6, 7, and 8, are views illustrating the operation of the tool; and

Figure 9 is a section taken on the line 9—9 of Figure 8.

The tire tool forming the subject matter of this application comprises a pair of levers 1 which are pivotally connected at 2 to form handles 3 at the opposite extremity of the tool from the working ends 4 of the tool. The levers 1 are provided on their inner sides, at their working ends 4, with recesses 5 forming shoulders 6 disposed approximately at right angles to the plane in which the levers open and close. The recesses 5 form ledges 7 disposed approximately at right angles to the shoulders 6, the ledges being extended longitudinally of the levers. There are transverse openings or slots 8 which are extended entirely through the levers at the outer ends of the ledges 7, to form transverse lugs 9 at the ends of the levers. The inner surfaces of 45 the lugs are rounded lengthwise of the tool, as

shown at 10. The levers are provided with transversely inclined surfaces 11 located at the inner ends of the ledges 7.

One end of a rim is shown at 14 and the other end of the rim appears at 12, the ends of the rim having outstanding flanges 15. Assuming that the ends 12 and 14 of the rim are in the overlapped relation shown in Figure 5 of the drawings, the said overlapped ends are engaged between the working ends 4 of the levers, and the handles 3 are pressed together. This lines up the ends of the rim, and the flanges on the end 14 of the rim slide along the inclined surfaces 11 until they are on the ledges 7 and in lateral abutment with the shoulders 6, the lugs 9 being at the extremity of the end 12 of the rim. The parts now are in the position illustrated in Figure 6 of the drawing. The tool is swung counter-clockwise from the position of Figure 6 to 70 the position of Figure 7 and finally to the position of Figure 8, the ends of the rim being brought into alignment, and the flanges 15 finally sliding through the openings or slots 8, into abutment with each other. 75

The tool is simple, but is well adapted for carrying out an operation which is often difficult to perform, and, owing to its simplicity, the tool will withstand hard use.

What is claimed is:—

1. A tool of the class described, comprising a pair of pivotally connected levers provided on the inner sides of their working ends with recesses forming shoulders disposed approximately at right angles to the plane in which the levers open and close, and forming ledges disposed approximately at right angles to the shoulders, the ledges being extended longitudinally of the levers, there being transverse openings extended entirely through the levers at the outer ends of the ledges and forming transverse lugs at the ends of the levers. 85

2. A tire tool of the class described, constructed as set forth in claim 1 and further characterized by the fact that the levers are 90 provided with transversely inclined surfaces at the inner ends of the ledges. 95

In testimony that I claim the foregoing as my own, I have hereto affixed my signature.

CHARLES A. HORNBURG.
